Inventor;

G. A. Nelson

United States Patent Office.

G. A. NELSON, OF CHICAGO, ILLINOIS.

Letters Patent No. 70,107, dated October 22, 1867.

CARD-RACK.

The Schedule referred to in these Letters Patent and making part of the same.

TO ALL WHOM IT MAY CONCERN:

Be it known that I, G. A. NELSON, of the city of Chicago, in the county of Cook, and State of Illinois, have invented a new and useful Card-Receiver and Register; and I do hereby declare that the following is a full and exact description thereof, reference being had to the accompanying drawings, making part of this specification, in which—

Figure 1 represents the front view of the case.

Figure 2 the section of the same.

Figure 3 is the ground section of the slats and their arms, and

Figure 4 the case for corners.

Figure 5 represents the metal strips on a larger scale, and detached.

Similar letters of reference mark corresponding parts of the machine.

The nature of my invention consists in turning slats or stationary boards, provided with springs attached to them, the whole arranged in a case; said slats or boards to be marked with letters of the alphabet, for the purpose of putting up any number of business cards in alphabetical order, to be held by said springs in the smallest space and in a most convenient manner.

To enable others skilled in the art to make and use my invention, I will proceed to describe its construction and operation.

A series of slats, A A, is put in a square case, B, and revolve on pins *a a*, one of their lower corners being pinned to a connecting-arm, *c*, to turn all the slats at once, although said arm may be dispensed with if desirable. Strips D D made of metal or any other suitable material, are cut, or partially punched in any desirable form, at proper distances, in such a way that the pieces *d d* thus cut out act as springs to hold the card slipped behind them. And the strips are pressed into the grooves *b b*, their edges entering the saw-cuts *f f*. There are two of such strips D D on each side of the slats. Corresponding to the spaces between the turning slats when they are open, the back-board E of the case is divided into spaces, and the strips F F arranged similarly to those. D D are sunk into grooves similar to the grooves *b b* made in the board E. The slats and the board-spaces are marked by letters of the alphabet, in correspondence with which the cards are assorted and put upon the slats or boards.

My invention may be applied to card-receivers for the corners in a circular or rather polygonal shape, as represented on fig. 4; *m m* being the turning slats, *n n* the stationary boards, and the whole arrangement revolving on a pin and socket, *p*, and supported by the brackets. It is a very convenient device to keep cards in offices. Any card wanted may be found easily.

What I claim as my invention, and desire to secure by Letters Patent, is—

1. The metal strips D, having the clips *d* formed thereon, by punching or cutting the latter therefrom, in the manner substantially as shown and described.
2. I claim securing the strips D, constructed as described, to the slats or case by inserting the edges of the strip into grooves *f*, substantially as described.
3. The turning slats A A, marked by letters of the alphabet, and constructed as described, in combination with the strips D D and the stationary board E, or boards *n n* arranged as described, the whole arranged substantially as herein set forth and for the purposes specified.

G. A. NELSON.
